OF SAID ERNEST P. PARSONS, DECEASED, ASSIGNOR TO THE PARSONS & PARSONS
COMPANY, OF CLEVELAND, OHIO

WATERPROOF COLLAR

Application filed April 12, 1926. Serial No. 101,276.

My invention relates to an improvement in water proof collars, and in general my object is to provide a shirt collar made of a material resembling a woven fabric which is 5 water proof and readily cleansed without the usual laundering operations. The material more commonly used is white in color, but may be of any color, and it possesses certain characteristics which make it permanently 10 stiff, although flexible within a certain degree to permit it to be used both for the body of the collar and for the button-hole tabs. The tabs are preferably separate pieces attached to the band of the collar to 15 facilitate manufacture and to permit each tab to be freely flexed and handled in button-holing operations. The strains imposed in attaching the collar to a shirt and subsequently in wearing the collar, center or 20 fall largely on the tabs especially at the button-holes therein. In this way the tab portion of the collar which is the least expensive part thereof, may lose its usefulness before the main body of the collar or destroy 25 the desired or proper set of the collar when attached to a shirt. To meet this condition and sub-serve the need of those who must economize I provide a collar in which the tabs may be properly affixed to the body of 30 the collar and also easily removed therefrom, thereby permitting the substitution of a new tab for an old worn one, and permitting tabs of varying length or shape to be used in lieu of one another.

35 In the accompanying drawing, Fig. 1 is a perspective view of a folded collar embodying my improvement. Fig. 2 is a vertical cross-section of a portion of the collar showing the interlocking connection for one of the tabs. Fig. 3 is an inner view of one end of the collar showing a button-hole tab attached thereto, and Fig. 4 is a horizontal section on line 4-4 of Fig. 3. Fig. 5 is an inner view of one end of the collar without 40 a tab; Fig. 6 a separate view of the tab and Fig. 7 a view of the locking piece for the tab.

45 As delineated, collar 2 is of the folded type, having an inner neck band 3 and an outer fold 4. The end edges 5 of band 3 are

cut on straight lines at a slanting angle back from each end edge 6 of the overlapping outer fold 4, beginning at the folded corner 7 of the upper fold line of the collar. A triangular space is thereby provided back 55 of each point of the collar and a separate button-hole tab 8 is attached to the band in overlapping relation to slanting edge 5, which tab extends into and beyond this space and the end edge 6. Tab 8 is flexible and 60 the triangular space permits it to flex more freely and for a greater part of its length in its lower half than in its upper half, which extends upwardly into contact with the folded corner 7. Consequently the button-hole 65 9 in tab 8 may be located opposite or relatively near the end edge 6 of the outer fold, or in a vertical plane directly beneath the corner fold 7, thus permitting the upper 70 end corners of the body of the collar to be brought closely together when the collar is buttoned as in use.

75 Tabs 8 are separate pieces of the same water proof material as body 2 of the collar and two short and narrow slots 10-10 are cut or punched on parallel lines in each tab near their inner ends. Similar slots 11-11 are formed in each end of neck band 3 relatively near the slanting end edge 5 and parallel with each other and the top fold line of the 80 collar so that when the tab is inserted between the outer and inner plys or folds of the collar with the upper edge of the tab in contact with corner 7 the slots in the tab may be caused to register with the slots in the band 85 and the tab will be placed in its proper alignment and setting relatively to the end edges of the collar. Then to lock the tab in place I employ a flexible strip 12 which may be of the same material as the tab or collar, 90 which strip is of the same width as the length of slots 10 and 11 and of such length itself to permit it to be inserted in one direction through one pair of registering slots and thence in the opposite direction through the 95 other pair of slots. Being flexible the ends of locking strip 12 may be pressed flat against the surfaces through which they have been projected, and in order that the locking strip 100 may not work out or become displaced the

upper end may be formed with an enlargement or head 14. Preferably, this locking strip is inserted through the slots so as to place head 14 and the lower free extremity 15 of the strip between the folds of the collar where they will be concealed and protected. The intermediate portion of locking strip 12 is exposed at neck band 3 and bears against the neck band of the shirt when the collar is attached thereto as in use. With this locking strip 12 or an equivalent device, the tabs may be removed and replaced at the option of the user, and a new tab may replace a worn button-hole tab, or new tabs of varying shape may be substituted for others to correct a poor fit or an improper setting on different sizes or variously tailored shirts. Locking of the tab in the way described also effectively prevents a shift or change in position of the tab relatively to the end to which it is attached.

What I claim, is:

1. A waterproof collar, comprising a collar band having horizontal slots vertically arranged above each other, button-hole tabs having similar slots adapted to register with the slots in the band and narrow flexible locking strips adapted to extend through the registering slots in said parts, each strip having an enlargement at one end adapted to prevent release of the strip in one direction and said strip being extended through said registering slots to openly expose its middle portion at the inside wall of said collar band.
2. A waterproof collar, of the folded type, comprising a neck band having a plurality of spaced slots in each end arranged vertically above each other, detachable button-hole tabs having correspondingly spaced slots therein, and flexible elements each including an enlarged head portion extending vertically through the slots in said band and tabs to lock the same securely together when assembled, whereby the middle portion of said elements are openly exposed at the inside wall of said collar band and said head portions prevent release of said elements in one direction, the upwardly extending edge of each tab contacting with the folded edge of the corresponding end of the collar and said elements being readily removable to permit the tabs to be detached and others substituted.

In testimony whereof I affix my signature.

ERNEST P. PARSONS.
